MITTEN

Hilda Woller-Duff, New York, N. Y.

Application August 19, 1948, Serial No. 45,082

1 Claim. (Cl. 2—158)

1
This invention relates to new and useful improvements in mittens.

More particularly, the present invention relates to mittens, especially for women, and, aims to provide a novel and valuable mitten of the stylishly smart class well adapted to be made of a textile material such as suede cloth, silk, satin or the like, that is, of a woven fabric of any suitable kind, or of a combination of a plurality of different such fabrics, and at the same time a mitten-type glove of such close and smooth fit all over the hand as to be characterizable as something analogous to the fit obtained over the calf of the leg by a full-fashioned knit piece of hosiery.

The statement that something fits like a glove has been long taken as tantamount to a statement that the fit obtained is the most perfect possible; but in the case of the present invention, while a mitten is involved, the fit obtained is closer than that obtained with an ordinary glove or mitten whether of leather or other material. Consequently, in connection with the present invention, the fit obtained will be referred to as a stocking fit, meaning such a fit, in a mitten-type glove, as that above referred to relative to the calf of the leg and in regard to a covering therefor constituted by a full-fashioned knit piece of hosiery. As is well known, the fit just mentioned is to some extent a function of an essentially elastic nature of knit fabric; but, as already stated, the material used pursuant to the present invention is a woven one, not a knitted one, yet the fit obtained is as above described, and this solely as the result of structural features of the new mitten, aside from the nature of the sheet material used.

According to the present invention, the structure of the glove is such that while it is a mitten-type one, that is, having a thumb stall and a single stall for the four fingers of the hand, the latter stall is stepped at its outer end, such steps relatively spaced longitudinally of the groove in accordance with the difference between the lengths of the four fingers, while, in combination with this feature, a gusset is provided extending down all the way to the wrist opening and preferably thus extended while having its upper and narrower terminus at a side of the mitten about opposite a midpoint along the length of the palm.

Still another object of the present invention proposes forming the mitten of separate back and palm portions secured together along their contacting peripheral edges and having the gus-

2
set set into one side thereof opposite the thumb stall in a manner to complete the formation of the improved mitten in accordance with the present invention.

A further object of the present invention proposes forming the gusset integrally with one of the mitten portions and stitching its free edge to the adjacent edge of the other mitten portion in a manner to expedite the stitching of the mitten and forming a smooth appearing mitten when completely stitched.

It is a further object of the present invention to construct a new and improved mitten which is simple and durable and which can be manufactured and sold at a reasonable cost.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

25 Fig. 1 is an elevational view looking at the back face of a mitten constructed in accordance with the present invention, with the gusset tucked in.

30 Fig. 2 is an enlarged bottom elevational view of Fig. 1.

Fig. 3 is a view showing the mitten of Fig. 1, but with the gusset extended.

Fig. 4 is an enlarged bottom elevational view of Fig. 3.

35 Fig. 5 is a fragmentary perspective view, looking at the same end of the mitten as seen in Fig. 4, but with the wrist portion of the mitten extended.

Fig. 6 is an enlarged horizontal sectional view taken on the line 6—6 of Fig. 3.

Fig. 7 is a view similar to Fig. 3, but illustrating a modification of the present invention.

Fig. 8 is still another view similar to Fig. 3, but illustrating a further modification of the present invention.

Fig. 9 is an enlarged horizontal sectional view taken on the line 9—9 of Fig. 8.

Fig. 10 is a plan view of the blank used for forming the back of the mitten shown in Fig. 8.

Fig. 11 is a plan view of the blank used for forming the palm of the mitten shown in Fig. 8.

In the various views, the illustrated mitten is one for the left hand, and so the back face of the mitten is the face thereof seen in Figs. 1, 3, 7 and 8.

The mitten, in accordance with the present invention, includes a thumb stall 10, and a finger stall 11 for receiving all the four fingers of the hand. The outer end of the finger stall 11, however, as here shown, has its continuity interrupted at intervals, as at 12, 14, 15 and 16, in accordance with the varying lengths of, respectively, the little finger, the fourth finger, the middle finger and the forefinger. The mitten is made so as snugly to enclose the four fingers and the thumb, as contradistinguished from the loose, baglike fit of the previous mitten made of fabric, which fabric has been a knitted one.

Also included in the mitten is a wrist portion 17, here shown as of short length; but, as will be understood, such wrist portion may be made of any length desired, as to provide one extended well up along the forearm or even, as in the case of a highly formal dress glove, up to the elbow or slightly beyond.

The mitten is further provided with a gusset 18, this, from a point at or near its bottom, tapering upward to a point 19. As the gusset 18 is here shown, the same, below the beginning of its said upward taper, is tapered downward, and over a distance representing a minor fraction, as say one-fourth or one-fifth, of the distance of upward taper of the gusset. Thus, in the case of the short mitten shown, when said gusset is tucked in as in Figs. 1 and 2, the lower end 20 thereof projects slightly below the wrist opening.

The new mitten as herein illustrated is comprised merely of three cut pieces of material, one for the back face of the mitten, another for the palm face of the mitten, and with the third piece the gusset. Said piece of material for the back face of the mitten is marked 21 in Figs. 1, 3, 5 and 6, and is of the outline shown in Figs. 1 and 3, plus an allowance all around for seamming, and for edge finishing the wrist opening; while said piece of material 21^a, see Figs. 5 and 6, for the palm side of the mitten is of the same outline. The edge of each such piece, at its side to be seamed to one of the two upwardly tapering sides of the gusset, is cut accordingly, preferably along a straight line.

Thus, when the gusset 18 is seamed to the piece 21, an inside seam is provided as indicated at 22 in Figs. 5 and 6, so that a seam line appears as at 23; and when the gusset is seamed to the piece 21^a a seam 24 like the seam 22 is provided, and a seam line 25 symmetrically matching seam line 23' appears on the palm face of the mitten. The companion pieces 21 and 21^a are stitched together all around the mitten, from the point 19 all along the stalls 11 and 10 to the point 26, to establish a continuous inside seam as indicated at 27 in Fig. 6, so that a seam line 27^a (Figs. 4 and 5) appears all around the mitten between the points 19 and 26.

The wrist opening may be finished in any desired way, but as here shown the same is folded in and stitched all around as indicated at 28^a to provide an inside edge seam 28.

Referring to Fig. 7, the same mitten as illustrated in Figs. 1 to 6 is shown, but with the gusset 29 of greater maximum width than the gusset 18. In this form, the piece 21 for the back face of the mitten, and the correspondingly shaped piece 21^a for the palm face of the mitten, are all so cut that the seam line 23' extends from the point 19 all the way to the point 26, that is, to the extreme side limit of the wrist opening on the side of the mitten beneath the thumb stall 10.

In other respects this form of the invention

is similar to the previous form of the invention and like reference numerals are used to identify like parts in each of the several views.

In the further modification of the invention shown in Figs. 8 to 11 the mitten is again similar to that illustrated in Figs. 1 to 6, except that the gusset 30 is integrally formed with the piece 21^a which forms the palm of the mitten. The gusset is arranged to be folded on the line 31 to have its free edge 32 stitched to the adjacent side of the piece 21 which forms the back of the mitten. Stitching the free edge 32 of the gusset 30 to the piece 21 forms the internal seam 22 and the external seam line 23 on the back side of the mitten. As the gusset 30 is integral with the piece 21^a which forms the palm side of the mitten there is no gusset seam line on the palm side of the mitten as in the previous forms of the invention.

In other respects this form of the invention is similar to that shown in Figs. 1 to 6 and like reference numerals are used to identify like parts in each of the several views.

It is also within the invention to place the gusset used, as, for instance, one like the gusset 18 or like the gusset 29 or of other size and shape within the invention, at the opposite side of the mitten, that is, at the thumb side thereof. The gusset means, further, may be plurally provided, as one gusset at the thumb side of the mitten and another at its little-finger side. Again, a gusset may be provided which extends wholly or mainly across the back face of the mitten, and/or a gusset which extends wholly or mainly across the palm side of the mitten.

The mitten, further, can be of solid color and/or of the same material, or of two-tone or other plural-color type and/or of two-material or other plural-material type. For instance, the back face of the mitten may be satin, silk or some such relatively smooth and lustrous material, and the palm face of the mitten may be of suede cloth or the like, or of some other material than that used for the back face of the mitten, with the gusset or a gusset or each gusset of a material like that used, as the case may be, for both faces of the mitten or for either face thereof, or of a different material from that used for either or both of such faces. In any of these cases, the colors provided at the two faces of the mitten may be alike or different, and the same in regard to the gusset or a gusset or each gusset relative to either or both faces of the mitten.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

In a glove formed of a back portion and a palm portion having aligned thumb engaging projections, one of said portions being cut off diagonally to have a straight edge extending from a point midway of the length thereof on the side opposite the side having the respective thumb engaging projection to a point midway of the width of the said one portion at the wrist end thereof, the other portion having on its side opposite its respective thumb engaging projection a gusset-like extension having a diagonally

extended straight edge matching the straight edge of the said one portion, said gusset-like extension being folded so that its diagonally extended straight edge extends parallel to the straight edge of the said one portion, and stitches securing said straight edges together with a minimum of overlap of the material of the portions defining said straight edges.

HILDA WOLLER-DUFF.
